UNITED STATES PATENT OFFICE

CLARENCE V. ROBERTS, OF GERMANTOWN, PENNSYLVANIA, AND WILLIAM D. ANTRIM,
OF GLOUCESTER, NEW JERSEY, ASSIGNEES TO ROBERTS & MANDER STOVE COM-
PANY, OF PHILADELPHIA, PENNSYLVANIA, A CORPORATION OF PENNSYLVANIA

DESIGN FOR A RANGE

Application filed May 5, 1931. Serial No. 39,729. Term of patent 14 years.

To all whom it may concern:

Be it known that we, CLARENCE V. ROBERTS and WILLIAM D. ANTRIM, citizens of the United States, residing, respectively, in Germantown, Philadelphia County, Pennsylvania, and Gloucester, Camden County, New Jersey, have invented a new, original, and ornamental Design for Ranges, of which the following is a specification, reference being

had to the accompanying drawing, forming part thereof, in which the figure is a perspective view of a range embodying our new design.

We claim:—

The ornamental design for a range, substantially as shown.

CLARENCE V. ROBERTS.
WILLIAM D. ANTRIM.
